CORE DRILL

Filed Nov. 17, 1928

UNITED STATES PATENT OFFICE

BURCHARD D. THOMPSON, OF BRADFORD, PENNSYLVANIA

CORE DRILL

Application filed November 17, 1928. Serial No. 320,182.

The invention relates to core drills for taking samples of earth formations and consists in the features and combination and arrangement of parts hereinafter described and particularly pointed out in the appended claim.

In the accompanying drawings

Figure 1 is a vertical sectional view of my improved drill.

Fig. 2 is a detail view.

Fig. 3 is a sectional view on line 3—3 of Fig. 1.

Figs. 4 and 5 are detail views.

The invention includes a suitable cutter 1 adapted to rest on the bottom of the well. This cutter consists of a hollow shell having a tooth formation at its lower end adapted to cut the formation so as to leave a core of said formation indicated at *a* of less diameter than the interior of the shell thus leaving an annular channel 3 about the core and between it and the shell 2 for the upflow of the detritus or so-called "sand pumpings" as will herein-after be referred to.

For this purpose the teeth of the cutter are wide at their lower ends to cut a path wider than the thickness of the shell to provide the clearance around the core mentioned above, and also to cut clearance around the outside of the shell and between it and the wall of the hole for the circulation of the detritus or "sand pumpings." The cutter shell is attached by screw threads to a tube 3*, which at its upper end is screw threaded to a block 4 having a vertical bore or port 5 which at its upper end has a flap valve 6, secured at 7 so that it may open upwardly for the passage of the detritus up through port 5, but said valve prevents downward passage of material through said port.

The block 4 has a tube 8 screw threaded thereto said tube being screw threaded at its upper end into connection with a block 9 forming a part of a stuffing box 16. Another tubing section 11 is screw threaded to the block 9 of the stuffing box and this tube section at its upper end is screw threaded to a head 12. Within the tubular casing or member 8 a piston 13 is mounted to reciprocate vertically and without undue friction.

This piston has ports 14 extending ver-

tically therethrough controlled by downwardly closing valves 14*. The piston rod 15 extends up through the stuffing box and through the head 12. It is provided at its upper end with any suitable means for attachment to an element or means for reciprocating it such as are usual on the derrick of earth drilling rigs. At a point near the upper end of the tubing 8 and under the stuffing box 9 lateral ports 16 are formed through the said tubing for the discharge outwardly therethrough of the detritus or sand pumpings. In the operation of the apparatus as thus far described, we will suppose that rotary step by step movement is given to the tool as it rests upon the bottom of the hole. Means for imparting this rotary motion will be later referred to. The teeth of the cutter will, therefore, cut the formation, while it maintains itself by its weight upon the bottom of the hole. During this cutting operation the piston will be reciprocated vertically by suitable means attached to the upper end of the piston rod with the result that the detritus and "sand pumpings" will be continuously drawn away from the teeth of the cutter up through the annular channel surrounding the core, past valve 6, through the piston and out through the openings 10, so that the cutting edge will be kept clear of cuttings and will perform its cutting action on the virgin formation instead of reacting on the detritus already produced by the cutting teeth. This flow of the detritus will be due to the action of the piston which when it goes up will draw the material up past valve 6, at the same time forcing out through the ports 10 any material which lies above it. On the down stroke the valve 6 will close and the piston valves will open allowing the material to get above the piston so that on the next upstroke of the piston the material will be forced out through the ports 10. In this way the cutting teeth are constantly cleared of cuttings thus enabling the teeth to act directly on the formation to be cut with efficiency.

The lateral openings 10 lie above the upper limit of movement of the piston so that they

are always free for the discharge of material therethrough.

I stated above that the tool may be rotated by any suitable means. In the form of my invention, which I have chosen for its illustration, I employ teeth *x* on the interior of the head 12 to be engaged by pawls *y* pivotally mounted at *z* in a disc A and arranged when the disc is rotated one way to cause the pawls 10 by engaging the teeth to rotate the head and the tubing and cutters. This disc has a pin 18 extending into a groove 17 in the piston rod. Said groove extends spirally of the rod and as the rod moves up and down it 15 rotates the disc first one way and then the other by the walls of the groove acting as cam surfaces against the pin 18. When the disc rotates one way it turns the apparatus through the pawl and ratchet connection, and 20 when the disc turns in the other direction the pawls give or turn on their pivots and move along the inner side of the head without rotating it. The pawls thus engage new teeth and on the next forward movement they turn 25 the head together with the tubing and cutter another step forwardly. It will be noticed that the ratchet mechanism is located in the cavity of the head member 12 above a block 20 fixed on the interior of the tubing.

30 On the piston rod at a point above the stuffing box a collar or enlargement 21 is located. When the apparatus is to be withdrawn from the well the piston rod is raised until the collar strikes the member 20 secured within the tubing and then continued upward movement of the piston rod will draw the apparatus out of the well.

At *b* I show grips representative of any suitable form for grasping the core and breaking and lifting it when the apparatus is drawn up out of the well.

I claim:

In combination a tube having teeth at its lower end to cut the formation at the bottom 45 of the hole when the tool is rotated, a block within the tube having a passage therethrough for the upflow of fluid and detritus, a valve closing downwardly and controlling said passage, a stuffing box in the tube above 50 said block, a piston working in the tube intermediate of said block and stuffing box, said piston having valve means to permit upward flow of the fluid and detritus, and to raise said fluid and detritus, said tube having a 55 discharge port leading to the outside of the said tube at a point below said stuffing box and above the piston when lowered, a piston rod extending up from the piston and through the upper part of the tube and means for rotating the tube, said means being operated from the reciprocations of the piston rod, 60 substantially as described.

In testimony whereof I affix my signature
BURCHARD D. THOMPSON,
